UNITED STATES PATENT OFFICE.

CHARLES S. UPTON, OF WALLA WALLA, WASHINGTON, ASSIGNOR OF
ONE-HALF TO RUSSELL B. CASWELL, OF WALLA WALLA, WASH-
INGTON.

COLTER AND STUBBLE-TURNER.

No. 836,544.

Specification of Letters Patent.

Patented Nov. 20, 1906.

Application filed April 4, 1906. Serial No. 309,811.

To all whom it may concern:

Be it known that I, CHARLES S. UPTON, a citizen of the United States, and a resident of Walla Walla, in the county of Wallawalla 5 and State of Washington, have invented certain new and useful Improvements in Colters and Stubble-Turners, of which the following is a specification.

My invention is an improvement in colters 10 and stubble-turners for plows; and the invention consists in certain novel constructions and combinations of parts, as will be hereinafter described and claimed.

In the drawings, Figure 1 is a side view, 15 partly in section, of my improved device, the lower box for the bearing of the colter-shaft being detached and shown partly in section for purposes of illustration. Fig. 2 is a top plan view of the improved devices. Fig. 3 is 20 a rear elevation thereof. Figs. 4, 5, and 6 are detail views of the clamp for securing the colter-standard to the beam, and Fig. 7 is a detail view of the colter-shaft.

The colter-standard A is cranked at its 25 lower end A' and is in practice secured to the plow-beam B by means of a suitable clamp C, which clamp may be designed to accommodate itself to any ordinary plow-beam. The clamp C has an upright tubular portion 30 C' and a set-screw C² operating in connection therewith, whereby to secure the shaft A in any suitable adjustment within the clamp C, as will be understood from Figs. 1 and 4 of the drawings.

The colter D, shown as a disk colter, is 35 journaled, as presently described, in the arms E' and E² of the fork of the colter-support E, the latter having at its front end a sleeve E³, secured upon the cranked lower end of the 40 standard A by means of the collar F, and the set-screw F', as will be understood from Fig. 1 of the drawings.

The colter-support has its arms E' and E² 45 provided with bearings for the shaft D' of the colter D, the said bearings being preferably provided with the lower caps G, adapted to receive the Babbitt metal G' and secured to the fixed caps G² by means of the bolts G³, as shown in Fig. 1. By this means the caps 50 may be readily removed for repairing the colter, renewing the Babbitt metal, or for any other desired purpose. The disk D is provided with the hub-sections D², riveted

together and to the disk and keyed upon the central portion D³ of the shaft D', so the 55 colter-disk and its hub will revolve with the turning of said shaft D' within its bearings in the colter-support. One of the arms of the colter-support is provided in rear of the bearings for the colter-shaft with an eye E⁴, having a vertical opening for the upright shaft H' of the carrier-bar H for the stubble-turner I and a set-screw E⁵ for securing the shaft H' in any desired adjustment within the eye E⁴. By this means the stubble-turner may be adjusted vertically or laterally with respect to the colter and be secured in any desired adjustment relative thereto.

The stubble-turner I is bolted or otherwise 70 suitably secured to its carrier-bar and is an approximately diamond-shaped steel sheet with proper curves to follow the colter D and is symmetrical, as best shown in Fig. 1, so that when it is dull or worn it can be reversed.

I claim—

1. The improvement substantially as herein described, comprising the cranked standard, a clamp for securing the same to a plow-beam, a colter-support having at its front end an upright sleeve fitting on the lower end 80 of the cranked standard and having the rearwardly-projecting fork whose arms are provided with bearings for the colter-shaft, and one of said arms being provided in rear of its bearing with an eye having a vertical opening, and a clamping-screw intersecting said opening, the colter having its shaft journaled in the bearings of its support, a stubble-turner consisting of a symmetrical reversible plate and a carrier-bar to which said stubble-turner is secured, said bar being provided at 85 its front end with an upright shaft fitted and secured within the eye at the rear end of the colter-support, all substantially as and for the purpose set forth. 90

2. The combination with the colter and the fork supporting the same and having one of its arms provided with an eye having an upright opening and a clamping-screw intersecting the same, of a stubble-turner and its 100 carrier having at its front end an upright shaft secured in the said eye and adapted for vertical and lateral adjustment, substantially as set forth.

3. The combination of a colter-support 105 having a rearwardly-projecting fork whose

arms are provided with bearings for the col-
ter-shaft, one of said arms being provided
in rear of its bearing with a vertical eye, a
clamping-screw intersecting the opening of
5 said eye, a colter journaled in the said bear-
ings, a stubble-turner, and a carrier-bar sup-
porting said stubble-turner and provided at

its front end with an upright shaft fitting and
secured within the vertical eye of the colter-
support, substantially as set forth.

CHARLES S. UPTON.
